HEAD BOX FOR PAPER MACHINES

Robert E. Showers, Green Bay, Wis., assignor, by
mesne assignments, to Marathon Corporation,
Menasha, Wis., a corporation of Wisconsin

Application May 11, 1951, Serial No. 225,857

4 Claims. (Cl. 92—44)

1

The present invention relates to paper making machines of the Fourdrinier type, and more particularly to head boxes or flow boxes for such machines.

An object of the invention is to provide a head box having an improved discharge or outlet portion by means of which a smooth stream of well-mixed stock will be delivered onto the forming surface of a Fourdrinier belt, whereby to obtain formation of a sheet of paper of uniform thickness and good quality at high speed.

Another object is to provide a head box with a discharge throat or passage having therein a grid section forming numerous longitudinal ducts to smooth and straighten the stock flow and to effect a mild mixing action on the stock, the walls of the ducts being so arranged as to avoid lodging of stock thereon and to prevent streakiness in the stock stream.

A further object is to provide a duct-forming grid section which is capable of simple installation in the head box discharge throat or passage, and which can be inexpensively manufactured.

The invention further consists in the several features hereinafter described and claimed.

In the accompanying drawings,

Fig. 1 is a vertical, sectional, elevational view of the head box end of a paper making machine embodying the present invention;

Fig. 2 is a fragmentary sectional elevation of a discharge throat or nozzle of the head box;

Fig. 3 is a transverse sectional view of the discharge throat, taken generally on the line 3—3 of Fig. 2;

Fig. 4 is an enlarged fragmentary sectional elevation of a portion of the discharge throat and a grid section therein;

Fig. 5 is a fragmentary sectional view taken generally on the line 5—5 of Fig. 2;

Fig. 6 is a fragmentary bottom view, with parts in section, of laterally adjacent grid section tubes;

Fig. 7 is a fragmentary detail sectional view of the upstream end of the grid section, and

Fig. 8 is a fragmentary detail sectional view of the upstream end of a modified form of grid section.

In the drawings, 10 designates a paper making machine head box having a discharge throat or channel 11 terminating at a slice 12 with a slot-like orifice from which a flat stream of pulp stock flows onto the upper run of a Fourdrinier wire belt 13, the belt being trained around the usual breast roll 14.

The head box is here shown to be of the gravity 55 31 are suitably supported at their rear portions,

2

flow type and includes parallel side walls 15 (one being shown), a bottom wall 16, and upper and lower front walls 17 and 18, the lower front wall being offset rearwardly from the upper front wall, and the discharge throat sloping downwardly and forwardly at an angle of the order of 25½° from a region between the front walls. The head box further includes a transversely extending vertical baffle wall or dam 19 spaced rearwardly from the lower front wall 18 and forming a pond chamber or delivery chamber 20 with the front walls and side walls, there being an up-pass 21 between the baffle wall and the lower front wall. The baffle wall 19 has a rounded lower edge spaced above the bottom wall to form a slot-like passage 22 extending across the width of the head box. A transversely extending vertical wall 23 is spaced rearwardly of the baffle wall 19 to form between them a down-pass 24, the passage 22 providing communication between the down-pass 24 and the up-pass 21. The lower end of the vertical wall 23 joins the bottom wall along a curved surface 25 sloping forwardly to the passage 22, and the upper end of the wall 23 is higher than the entrance of the discharge throat 11 but is normally submerged. The bottom passage 22 is considerably narrower than the width of the up-pass and down-pass and serves to increase the stock velocity at this region, so as to effect mixing of the stock shortly before it is discharged from the head box. However, the velocity should not be so high as to cause excessive disturbance of the stock when it enters the discharge throat. The optimum velocity can be provided by vertically adjusting the baffle wall 19. The lower end of the up-pass 21 has a normally closed drain opening 26 formed in a side wall of the head box.

The inclined discharge throat or channel 11 is formed between upper and lower cross plates 27 and 28 and vertical side plates 29, all formed of metal, the cross plates 27 and 28 having smoothly curved rear end portions attached to the respective upper and lower front walls of the head box, and the side plates 29 being parallel to each other and being attached to the parallel side walls of the head box. The plates 27 and 28, which include inclined parallel portions, are supported by a suitable frame work having sets of laterally spaced top and bottom frame members 30 and 31 extending forwardly from the front walls of the head box, each set of frame members being secured to separator bars 32, and the endmost frame members being also secured to the side plates 29. The lower frame members 50 31 are suitably supported at their rear portions,

as by a cross beam 33 carried on columns 34, one of the latter being shown. The cross-sectional area of the throat or channel 11 is of horizontally elongated rectangular shape, as indicated in Fig. 3. The throat has mounted therein a flow-smoothing and stock-mixing grid section 35 hereinafter more fully described.

The slice 12 comprises a forwardly sloping top plate or lip 36 spaced above a bottom plate 37, the sides of the slice orifice being defined by vertical side plates 38 between which the top plate slidably fits. The slice plate 36 is hingedly carried at its rear portion, as hereinafter described. The bottom plate 37 is a part of a ribbed beam-forming base 39 which is suitably supported as by columns 40 (one being shown). The ends of the base carry upstanding end castings 41 which together with the frame members 30 mount slice-adjusting means 42 of any suitable type. The plates 36 and 37 are provided with respective liners 43 and 44, Fig. 2, which form continuations of the throat plates 27 and 28. The various plates defining the interior surfaces of the discharge throat are of corrosion-resistant and slime-inhibiting metal, such as copper, and are suitably fastened in place, as by bolts 45. The lower plate 37 has an approximately horizontal front portion 46, the liner of which lies slightly above the plane of the upper run of the Fourdrinier wire belt and terminates a short distance rearward of the vertical central plane of the breast roll 14. The rear portion of the plate 37 is curved upwardly and has a transverse bottom flange 47 which is rigidly bolted to the front ends of the frame members 31 for the lower throat plate 28. The slice plate 36 has a forwardly and downwardly inclined front portion 36' which has a lesser slope than the main portion of the throat and has its front end spaced a short distance above and rearward of the horizontal front end 46 of the plate 37 to form therewith the slice orifice or outlet. By way of example, the slot-like slice orifice may be about $\frac{5}{8}$ " high in the case of a tissue making machine. The plates 36 and 37 form a forwardly converging front portion of the discharge passage 11, the slope of the front portion 36' of the slice plate 36 being of the order of $13\frac{1}{2}$ °. The front end of the slice plate 36 is vertically adjustable, as by a series of suspension rods 48 (one being shown) forming a part of the slice adjusting means 42. The rear end of the slice plate 36 is upwardly curved and has a transverse top flange 49 which is slightly spaced from a transverse angle bar 50 secured to the front ends of the upper frame members 30. A number of spaced studs 51 (one being shown) are threaded into the upper edge of the rear flange 49 of the slice plate 36 and extend upwardly therefrom through the forwardly projecting top flange of the angle bar 50. At their upper ends the studs have nuts 52 resting on segmental rockers 53 (one being shown) saddled in apertured bearing members 54 which are secured to the angle bar top flange, the studs passing through the rockers and the bearing members. Upward displacement of the slice plate flange 49 is resisted by set screws 55 (one being shown) carried by the angle bar 50. A yieldable rubber sealing strip 56 is interposed between the slice plate flange 49 and the angle bar 50 and is held under pressure by coiled springs 57 surrounding bolts 58 which pass through the flange and angle bar.

The flow-smoothing and stock-mixing grid section 35 is here shown to comprise a number of rows of parallel metal tubes 59, preferably of cop-

per and of square cross-section, which are brazed or welded together in parallel relation to form a rigid assembly fitting in the discharge throat or channel 11. By way of example, these tubes 59 may be about 1" square and the throat may be about 6" deep. The grid section presents in cross-section a cellular or honeycomb appearance, and forms numerous parallel ducts open at opposite ends and all extending in the direction of the line of flow, all the ducts being parallel to the planes of the vertical side plates 29 and of the inclined parallel portions of the upper and lower throat plates 27 and 28. The upper and lower throat plates 27 and 28 and the slice plates 36 and 37 are recessed at 60 to correspond with the thickness of the tube walls so that the inner surfaces of the uppermost and lowermost tube walls will be flush with the throat walls. As best seen in Fig. 4, the uppermost tube walls bridge the joint between the cross plate 27 and the slice plate liner 43, and the lowermost tube walls bridge the joint between the cross plate 28 and the liner 44 of the lower plate 37. At the opposite sides of the grid assembly the vertical tube walls are cut away so that the inner flat vertical surfaces of the throat side walls will define walls of some of the ducts. In some instances, some of the tube walls at the upper portion of the throat may terminate short of the side walls, as seen in Fig. 5. The length of the grid section in the direction of flow is several times as great as its top-to-bottom transverse dimension, and the length of each tube is many times its transverse dimension, as shown in Fig. 2. The tubes in vertically adjacent rows are staggered, as shown in Figs. 3 and 5, thus avoiding any streakiness in the stock stream. The upstream ends of the tubes are cut square and have smoothly rounded and polished edges 61 so as to prevent lodging or clumping of stock thereon. The downstream end of the grid section extends for some distance into the forwardly converging front portion of the discharge throat, and this end of the grid section is wedge-shaped and has bias-cut edges 62, as seen in Fig. 2, so that the uppermost tubes extend farther forward than the other tubes, thus exerting a slightly greater retarding effect on the upper portion of the stream than on the lower portion so as to compensate for the difference in the length of the stream paths along the upper and lower portions of the curved front end of the discharge throat. At their downstream ends, the uppermost and lowermost walls of the tube assembly are cut square to fit in the recesses 60. Except for these uppermost and lowermost walls, the downstream ends of the top and bottom walls of the tubes have deep serrations or V-cuts 63 and sharpened edges 64, as seen in Fig. 6, to minimize disturbance of the forwardly flowing stock as it leaves the ducts of the grid section and approaches the slice orifice. This arrangement also avoids a sudden reduction of pressure which might cause formation or enlargement of air bubbles in the stock. The sharpened bias-cut edges of the vertical walls of the tubes at the downstream ends of the tubes also serve to minimize disturbance of the stock as it leaves the tubes.

In the operation of the machine the pulp stock 70 is supplied to the head box delivery chamber or pond chamber 20 through the up-pass 21 and is maintained at a suitable level in this chamber in accordance with the speed of the Fourdrinier belt, this level determining the spouting velocity 75 at the slice. The stock flows downwardly and

forwardly through the inclined discharge throat 11, and for a considerable distance passes through the numerous parallel ducts or channels formed by the tubes 59 of the grid section 35, thus effectively breaking up any large vortices and straightening the flow so that the stock stream issuing from the slice will have a smooth glassy appearance, free of streakiness and cross currents, and the paper formed will be of uniform thickness and quality. In its passage through the grid section tubes, the stock, by its frictional contact with the extended surface of the tube walls, will be subjected to a mild mixing action which will have a beneficial effect on the texture of the paper. The construction of the grid section is such that it is self-cleaning, avoiding any lodging or clumping of the stock. As the stock flows through the forwardly converging front portion of the discharge throat, the velocity of the stock gradually increases. However, the included angle of this portion of the throat is such as to maintain a non-turbulent flow while avoiding an excessive distance between the slice orifice and the front end of the grid section. The stock stream issues from the slice orifice substantially parallel to the top run of the wire belt and in the direction of travel of this top run.

The stock-mixing action in the grid section is caused by a rolling or vortex action in the layers of the stock along the surfaces of the top, bottom, and side walls of the numerous duct-forming tubes, thus providing a random orientation of the stock fibres in the issuing stock stream so as to improve the felting of the fibres during formation of the sheet. The mutually perpendicular transverse dimensions of each tube are of the same order of size, thereby avoiding any major disturbances in the stock flow, and each tube is of sufficient length to provide adequate flow-straightening and stock-mixing action. By way of example, each tube may have a length of the order of 20 times its width. While the ducts formed by the tubes are preferably of square cross-section, as shown, they may have various other cross-sectional shapes, such as rectangular, hexagonal, trapezoidal, and triangular.

The construction of the present invention enables a smooth, high-velocity flow of well-mixed stock to be delivered to the forming surface of a Fourdrinier wire, so as to secure the formation of a strong sheet of paper of uniform thickness and good quality at higher operating speeds.

The modified form of grid section 35' shown in Fig. 8 is similar to that of Fig. 2 except that rounded and polished beads 61' are secured, as by brazing or welding, to the edges of the upstream ends of duct-forming grid section tubes 59' to form the margins of the duct entrances, the width of the rounded beads being greater than the thickness of the duct walls. The rounded beads prevent lodging of stock thereon and initiate a rolling or vortex action of the stock along the duct walls to effect mixing of the stock. The grid section 35' provides a smooth, high-velocity flow of well-mixed stock, as in the construction of Fig. 2.

What I claim is:

1. In a paper making machine, a flow passage for supplying stock to a web-forming surface and

having a discharge orifice, said passage including a portion with parallel upper and lower walls, and a grid section in said passage having vertical walls and having other walls parallel to said parallel passage walls, said grid section walls forming a plurality of rows of parallel flow-smoothing ducts extending longitudinally of said passage in the direction of the line of flow in said passage, the downstream edges of said vertical grid section walls extending angularly of the ducts, and the downstream edges of the other grid section walls being serrated.

2. In a paper making machine, a head box having an outflow passage communicating therewith for supplying stock to a web-forming surface, said passage having a forwardly and downwardly inclined portion extending from said head box and provided with parallel upper and lower walls, and said passage further having an exit portion with forwardly converging upper and lower walls and with a discharge orifice, the front portion of said last-named upper wall having a lesser slope than the inclined portion of the passage, and the front portion of said last-named lower wall being substantially horizontal, and a grid section in said inclined portion of the passage having walls forming a plurality of rows of flow-smoothing ducts all parallel to each other and extending longitudinally of said passage in the direction of the line of flow in said passage.

3. In a paper making machine, a flow passage for supplying stock to a web-forming surface and having a discharge orifice, and a grid section in said passage having walls forming a plurality of rows of parallel flow-smoothing ducts extending longitudinally in said passage, all of said ducts being in parallel relation to each other and extending in the direction of the line of flow in said passage, the upstream ends of said walls having edges with rounded beads thereon defining the entrances of said ducts, and said beads being thicker than the walls of said ducts.

4. In a paper making machine, a flow passage for supplying stock to a web-forming surface and having a discharge orifice, said passage including a portion with parallel upper and lower walls, and a grid section in said passage having vertical walls and having other walls parallel to said parallel passage walls, said grid section walls forming a plurality of rows of parallel flow-smoothing ducts extending longitudinally of said passage in the direction of the line of flow in said passage and the downstream edges of said other grid section walls being serrated.
